UNITED STATES PATENT OFFICE

2,445,599

SANDER

Rayner V. Bowen, Huntington, W. Va.

Application January 20, 1947, Serial No. 723,123

5 Claims. (Cl. 51—187)

1

This invention relates to improvements in sanding devices, and its prime object is to provide simple and improved means for holding an abrading means such as sandpaper and the like; to provide improved latching means to be used in conjunction therewith; to provide a novel extension means, removable in nature, for reaching corners otherwise difficult to abrade; to provide an efficient, inexpensive sanding device which lends itself well to commercial manufacture.

Ancillary objects and those specifically enumerated hereinabove will become apparent to those skilled in the art, in following the description of the preferred embodiment of the present invention illustrated in the accompanying drawings, wherein:

Figure 1 is a perspective view of the preferred embodiment of the present invention;

Figure 2 is a perspective view of the invention disclosed in Figure 1, in its open position;

Figure 3 is a perspective view of the extension means forming part of the present invention;

Figure 4 is a transverse sectional view of the invention disclosed in Figure 1 and taken substantially on the line 4—4 thereof and in the direction of the arrows; and

Figure 5 is a longitudinal sectional view of the invention disclosed in Figure 1 and taken substantially on the line 5—5 thereof and in the direction of the arrows.

Referring now in detail to the illustrated preferred embodiment of the present invention, like reference characters are used throughout to indicate similar elements.

This invention has been devised to provide a handy and efficient sander and is adapted to use conventional size standard sandpaper and the like. Certain curves and contours are provided in this device for reaching in close or confined spaces and other portions are so contoured to be especially adaptable for use in sanding various shaped articles.

A pair of blocks 10 and 12 respectively, preferably wooden, are provided with rounded edges 14 and 16 at the first marginal edge thereof and inclined edges 18 and 20 at the opposite marginal faces. A hinge 22 is provided on the inner faces of said blocks adjacent the rounded edges 14 and 16. The construction of the said hinge 22 is preferably a simple strip of fabric however, it is apparent that a piano hinge or the like may be used in lieu thereof.

A continuous strip of web member 24 is provided on the outer faces of said block members and is curved in slightly between said blocks. Any 55 with the blocks 10 and 12.

2

suitable webbing material may be used however, felt is the preferable material. Received on top of the said web member 24 is a sheet of standard abrading paper or the equivalent which is indicated at 26.

Complemental slots 28 and 30 respectively are provided longitudinally of said blocks and improved clamping means are secured within the said slots. It is here noted that the position of 10 said improved clamping means forms an important part of the instant invention since said clamping means were designed to be both efficient and extremely easy to operate. A pair of guide pins 32 and 34 respectively are received in the 15 said slots 30 and a substantially U-shaped channel member 36 having slots 38 and 40 therein, is suitably received in said slot 30. It is apparent from an inspection of Figure 2, that the said guide pins 32 and 34 are received in said slots 38 and 20 40 thereby restricting the travel of the said U-shaped slide 36 to a predetermined travel. A latch 42 is received on said U-shaped member and is adapted to engage a staple 44 in the said slot 28. The legs 46 and 48 of said member 36 are adapted 25 to be used as thumb buttons or actuating means. The operation of the said latch is deemed quite obvious. The said slot members are simply folded together and the member 36 is actuated to the staple clasping position or staple disengaging 30 position.

Forming another important portion of the present invention is the extension means 50 shown best in Figure 3. A simple plate 52 is provided with a right angular marginal flange 54 at one 35 end thereof. The said marginal flange 54 is adapted to be received in the said slots 28 and 30, while the body portion of said extension 50 is adapted to protrude from between said blocks at the said inclined edges 18 and 20. Since the 40 flange 54 is received in the said slot, a cut-out 56 is provided in said flange to avoid any possible interference with the latching means. The marginal edge opposite said flange is folded back to form a rather sharp leading edge 58 for reaching 45 certain corners which might be otherwise difficult to abrade. It is here noted that the said extension 50 is covered with suitable abrading means 26 as described hereinbefore. It is noted at this point that the invention contemplates the use 50 of different gauge abrading means for each component of the invention. Accordingly, if it is desired, a relatively heavy or relatively light abrading means may be used on the said member 50 while different means are used in conjunction

It is apparent that a device has been described hereinabove capable of performing all of the objects specifically innumerated as well as many others. It is further apparent that there has been described a single preferred embodiment of the instant invention, and various changes including omissions and additions may be made without departing from the purview of the instant invention. Accordingly, limitation is sought only in accordance with the scope of the following claims.

Having thus described this invention what is claimed as novel and improved is as follows:

1. A sander comprising a pair of hinged abrasive sheet supporting blocks having slots in their adjacent faces, latch means mounted on said blocks and received between said blocks, detachable abrading means secured between said blocks and extending therefrom, said latch means including a slide secured in one of said slots, a latch on said slide and a staple in the other of said slots.

2. A sander comprising a pair of hinged blocks, latch means on said blocks received between said blocks, abrading means on said blocks, removable abrading means secured between said blocks and extending therefrom, said removable abrading means comprising a plate having abrading surfaces thereon, a flange at one marginal edge thereof adapted to be received within said slots and the other marginal edge being folded thereby forming a sharp sanding surface at the end thereof.

3. A sander comprising a pair of hinged blocks, latch means on said blocks received between said blocks, abrading means on said blocks, removable abrading means secured between said blocks and extending therefrom, said latch means including a slide secured in one of said slots, a keeper on said slide and a staple in the other end of said slots, said removable abrading means comprising a plate having abrading surfaces thereon, a flange at one marginal edge thereof adapted to be received within said slots and the other marginal

edge being folded thereby forming a sharp sanding surface at the end thereof.

4. In a sanding device, a pair of hinged blocks having curved edges, hinge means at said curved edges, inclined edges opposite said curved edges, abrading means on said blocks, latch means between said blocks, removable abrading means between said blocks and extending from between said inclined edges, said removable abrading means comprising a plate having abrading surfaces thereon, a flange at one marginal edge thereof adapted to be received within said slots and the other marginal edge being folded thereby forming a sharp sanding surface at the end thereof.

5. In a sanding device, a pair of hinged blocks having curved edges, hinge means at said curved edges, inclined edges opposite said curved edges, abrading means on said blocks, latch means between said blocks, removable abrading means between said blocks and extending from between said inclined edges, said latch means including complementary slots in said blocks, a slide secured in one of said slots, a keeper on said slide and a staple in the other of said slots.

RAYNER V. BOWEN.
